ATTORNEY

UNITED STATES PATENT OFFICE

146,999

DESIGN FOR A TEA KETTLE

Robert B. Wemyss, Louisville, Ky., assignor to Reynolds Metals Company, Richmond, Va., a corporation of Delaware

Application March 2, 1946, Serial No. 127,055

Term of patent 3½ years

(Cl. D44—25)

To all whom it may concern:

Be it known that Robert B. Wemyss, a citizen of the United States, residing in Louisville, county of Jefferson, State of Kentucky, has invented a new, original, and ornamental Design for Tea Kettle, of which the following is a specification, reference being had to the accompanying drawing, forming part thereof, wherein—

Fig. 1 is a top plan view of a tea kettle, showing my new design; and

Fig. 2 is a perspective view thereof.

I claim:

The ornamental design for a tea kettle, as shown.

ROBERT B. WEMYSS.
